(57) **CLAIM**

The ornamental design for an interlocking toy frame as shown and described.

DESCRIPTION

FIG. 1 is a top perspective view of an interlocking toy frame. FIG. 2 is a top view of the interlocking toy frame. FIG. 3 is a first, side view of the interlocking toy frame. FIG. 4 is an end view of the interlocking toy frame. FIG. 5 is a bottom view of the interlocking toy frame. FIG. 6 is a second, side view of the interlocking toy frame; and, FIG. 7 is a bottom perspective view of the interlocking toy frame.

The broken lines in the figures show features of the interlocking toy frame that form no part of the claimed design. Further, the broken away symbols in the drawings indicate the appearance of any portion of the interlocking toy frame between the break lines forms no part of the claimed design.

1 Claim, 7 Drawing Sheets
